US0D1098737S

(12) **United States Design Patent** (10) **Patent No.:** **US D1,098,737 S**
(45) **Date of Patent:** **** Oct. 21, 2025**

(54) **BACKPACK**

(71) Applicant: **YETI Coolers, LLC**, Austin, TX (US)

(72) Inventors: **Kyle Edward Rogers**, Austin, TX (US); **John Loudenslager**, Austin, TX (US); **Calvin Tabor**, Austin, TX (US); **Victor Kang**, North Vancouver (CA); **Dustin Bullock**, Austin, TX (US)

(73) Assignee: **YETI Coolers, LLC**, Austin, TX (US)

(**) Term: **15 Years**

(21) Appl. No.: **29/851,613**

(22) Filed: **Aug. 30, 2022**

Related U.S. Application Data

(63) Continuation of application No. 29/726,166, filed on Feb. 28, 2020, now Pat. No. Des. 961,913.

(51) **LOC (15) Cl.** **03-01**

(52) **U.S. Cl.**

USPC **D3/217**

(58) **Field of Classification Search**

USPC D3/215-217; D7/607

Yeti Crossroads 27L Backpack Review, by Laurence Fry (Carryology.com, Jul. 29, 2022), retrieved May 29, 2025 at URL: <https://www.carryology.com/bags/yeti-crossroads-27l-backpack-review/>.*

(Continued)

Primary Examiner — Jennifer L Watkins

(74) *Attorney, Agent, or Firm* — Banner & Witcoff, Ltd.

(57) **CLAIM**

The ornamental design for a backpack as shown and described.

DESCRIPTION

FIG. 1 is a top, front, right perspective view of a backpack showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The even-length broken lines and uneven-length broken lines in FIGS. 1-7 form no part of the claimed design. The zig-zag lines represent unclaimed stitching.

1 Claim, 7 Drawing Sheets

US D1,098,737 S
